UNITED STATES PATENT OFFICE.

ROY A. MANNING, OF RUTLAND, VERMONT, ASSIGNOR TO MANNING MANUFACTURING COMPANY, OF RUTLAND, VERMONT, A CORPORATION OF VERMONT.

BOTTLE-WASHING MACHINE.

Application filed July 30, 1920. Serial No. 400,007.

This invention relates to certain new and useful improvements in bottle washing machines and to that class of machines known as the inverted retainerless machines, where-
5 in a case of bottles or analogous articles are fed into the machine, the bottles being sub-
jected first to jets of washing fluid, then jets of rinsing fluid, and then to jets of steam for
sterilizing the bottles, the object of this in-
10 vention being to provide a novel form of jet
box for spraying the bottles as they pass
through the machine.

A still further object of the invention is to provide a novel construction of jet box
15 wherein all foreign matter which accumu-
lates therein can be readily removed.

Other and further objects and advantages of the invention will be hereinafter set forth and the novel features thereof defined
20 by the appended claim.

In the drawings,

Figure 1 is a longitudinal section through the apparatus showing a case of bottles in position over the rinsing jet box;

25 Figure 2 is a transverse vertical section showing a case moved between the upper and lower jet boxes for thoroughly cleaning the inner and outer surfaces of the bottles in the case.

30 In carrying out my invention I employ an oblong tank 1 substantially semi-circular in shape in cross section mounted on legs 2 and provided with a partition 3 forming compartments 4 and 5, the compartment 4 being adapted to contain a washing fluid such as alkali water and the compartment 5 clear water for rinsing the bottles as will be hereinafter fully described. Each compartment is provided with a drain plug 6.

40 The upper edges of the tank 1 are provided with angle irons 7 connected together by cross bars 8 carrying angle irons 9 forming a guide way for a case 10 as clearly shown in Figure 2. The case 10 is adapted to contain bottles or analogous articles ar-
45 ranged in inverted position as clearly shown in Figure 2 with their mouths downwardly so that the jets of fluid pass into the bottles as will be later described.

50 Connected to the angle irons 9 forming the guide way are rail guides 11 in which are slidably mounted substantially I-shaped rails 12 on which are adjustably mounted dog supports 13 which are clamped in adjusted
55 position by bolts 14, said supports carrying

pivoted dogs 15 which are capable of swing-
ing in one direction but are stopped from
swinging in the opposite direction by en-
gaging the lugs 16, said dogs being adapted
to engage the case of bottles as clearly 60
shown, the dogs being arranged in pairs in
transverse alignment with one another and
spaced apart longitudinally a sufficient dis-
tance to allow a case to be placed between
the same whereby individual case pushers
65 are provided whereby I am able to move
the cases the proper distance so that the
mouths of the bottles will be centered over
the holes in the jet boxes as will be herein-
after fully described.

70 The tank is enclosed by a hood or cover 17
herein shown formed of three sections, the
central section being provided with longi-
tudinally disposed slots 18 through which
75 extend pusher arms 19 slidably mounted
in suitable guides 20 carried by the angle
irons 7 of the tank, said pusher arms 19
having their inner ends connected to the
rails 12 as shown, the outer ends being pro-
80 vided with a bifurcated portion 21 into
which is adapted to extend the slotted up-
per ends of rocker levers 22 which are
mounted in suitable bearings 23 carried by
the legs 2.

85 The rocker levers are connected to the pusher arms 19 by pins 24 extending through
apertures in the furcations of the arms 19
and the slot of the rocker levers as clearly
shown in Figure 1 in order to provide a
sliding and pivotal connection. The rocker 90
levers 22 are provided with oppositely dis-
posed notches 25 and 26 formed by outwardly
extending fingers, the upper fingers ex-
tending substantially laterally from the
rocker levers and the lower fingers extend
95 downwardly in order to provide a curved
guide for the purpose hereinafter fully de-
scribed. The rocker levers 22 are arranged
in a slotted member 27 carried by the end of
the pitman 28, the member 27 having pins 100
29 and 30 extending across the slot thereof
which are adapted to cooperate with the
notches 25 and 26 of the rocker levers.

105 While I have shown the pitman rod
formed of two sections, one of which is in
the form of a slotted member it is of course
understood that a pitman rod formed of a
single piece having a slot can be used and I
do not wish to limit myself to these details
of construction as I am aware that various
110

changes can be made without departing from the spirit of my invention.

The pitman rods 28 which are arranged on each side of the tank are connected to crank arms 31 carried by crank shaft 32 mounted in suitable bearings 33 secured to the end of the tank 1 as shown in Figure 3. When the crank shaft is rotated the pitman rods are reciprocated as clearly shown so that the 10 rocker levers are rocked intermittently or a pause is produced which is determined by the length of the slot in the pitman rod so that the case pullers will only move intermittently, moving a case a predetermined 15 distance so as to center the bottles over the jets and then stop for a predetermined time so as to allow the fluid to thoroughly wash and rinse the bottles in the case. The crank shaft 32 carries a gear 34 meshing with a 20 pinion 35 carried by a shaft 36 mounted in a suitable support 37 connected to one of the legs, said shaft being provided with a worm wheel 38 meshing with the worm 39 carried by shaft 40 by means of which the crank 25 shaft is rotated as will be hereinafter fully described.

Arranged at one side of the tank is a base 41 provided with suitable bearings 42 in which is mounted drive shaft 43 herein shown provided with a pulley 44 over which is adapted to extend a belt 45 for driving the same, said shaft being provided with a pinion 46 meshing with the gear 47 secured on the end of the shaft 40 as clearly shown in 30 Figure 1. Supported by the base are rotary pumps 48 and 49 which may be of any of the well known types of pumps now in use, the pump 48 being provided with an inlet 50 extending into the compartment 4 of the tank and an outlet 51 from its top extending into the compartment 4 of the tank and connected to one of the jet boxes as will be later described. The pump 49 is provided with an inlet 52 extending into the compartment 5 of the tank and an outwardly extending outlet 53 which is provided with a downwardly extending branch 54 extending into the compartment 5 and a branch 55 extending through the hood or cover and adapted 40 to be connected to the jet boxes as will be later described.

Connected to the angle irons 7 carried by the upper edge of the tank 1 are inwardly extending supports 56 carrying jet boxes 57 and 58 disposed within the compartment 4 of the tank, the jet box 57 being connected to the outlet pipe 51 of the pump 48, the jet outlet being provided with a branch 59 and connected to the jet box 58. 55 The jet boxes are provided with removable covers 60 held in position by bolts and having jet openings 61 so positioned that when a case of bottles is drawn within the machine the mouths of the bottles will be positioned over the jets. The jet boxes are pro-

vided with tapering bottoms 62 which taper towards the longitudinal center and towards one end, each box having an outlet 63 closed by a plug 64 whereby the foreign matter which accumulates in the jet boxes can be 70 readily flushed out by removing the brass plug and starting the pumps. In case the foreign matter should become hardened on non-use of the machine, the jet plates can be removed and the boxes thoroughly 75 cleaned.

Arranged in the compartment 5 is a similar jet box 65 which is supported in a similar manner and is connected with pipe 54 to the pump 49. Arranged above the jet box 65 near the upper portion of the cover is an inverted jet box 66 which is connected to the pipe 55 and is supported by arms 67 in such a manner that a case is free to move between the jet boxes, the upper jet box delivering a series of jets of water onto the outer surface of the receptacles within the case while the lower jet box subjects the inner surface of the bottles or receptacles in the case to the fluid. 80

A steam jet box 68 is arranged within the compartment 5 and connected to a steam pipe 69 so that before the cases are moved out of the machine the bottles are subjected to live steam so as to thoroughly 95 sterilize the same.

The hood or cover 17 is provided with a deflector 70 so that any fluid thrown upwardly by the jets between the movements of the cases over the jet boxes will drain 100 back into the tank.

The operation of the machine is as follows: The case of bottles is placed on the guide way at A and forced into the machine until it is caught by the dogs where it is carried over the first jet box and as the compartment 4 contains a washing fluid which is continuously being circulated by means of the pump the bottles are subjected to streams of washing fluid so as to clean the same, the case then advances over the second jet box where the operation is repeated, it then moves intermittently a predetermined distance as shown in Figure 2 so that the contents will drain out of the bottles and off 110 the cases back into the compartment containing the washing fluid. The same then advances by the pushing dogs until it is positioned over the jet box 65 and under the jet box 66 and as clear water is being circulated from the compartment 5 through these jet boxes, the bottles are subjected to a rinsing action and the case of bottles is then advanced over the steam jet box where 115 the bottles are sterilized. 120

It will be seen that as the cases are fed into one end of the machine and delivered out of the opposite end the cases move in a guide way through the machine intermittently and in such a manner that by the 130

particular construction of pushing dogs and operating means the cases are positively positioned over the jet boxes so as to allow the jets to deliver streams of washing fluid and water into the mouths of the bottles and as the machine is being driven continuously the cases can be fed into the machine one at a time and they will move intermittently therethrough so as to first subject the bottles to a cleaning fluid and then to a rinsing fluid and then to live steam for sterilizing the bottles before they leave the machine.

As the crank shaft rotates the pitmen move forward and through their connection with the guide rails, the guide rails are moved rearwardly and in this movement the pusher dogs swing on their pivots so as to pass by the case which remains stationary over the jet boxes and as the crank continues to rotate the rocker arms are not engaged until the crank has reached the position shown in the diagrammatic view where the rocker arms are rocked so as to move the rails forward and in this movement the dogs engage the cases and advance the same through the machine and by this particular construction a pause in the operation is obtained so that the cases remain stationary over the jet boxes a sufficient length of time

to allow the jets to act thoroughly on the bottles within the cases.

While I have shown certain details of construction of the various parts of the machine I do not wish to limit myself to these details as I am aware that various changes can be made without departing from the spirit of my invention.

From the foregoing description it will be seen that I have produced a bottle washing machine composed of a tank semi-circular in cross section having a cover or hood substantially semi-circular in cross section of oval shape wherein the fluid coming from the jet box is carried around the walls of the cover and falls back on the bottom of the bottles or analogous articles arranged within the cases so as to wash the same.

What I claim is:—

A spray head for bottle washing machines comprising having a jet box provided with a removable cover having a plurality of openings forming jets, said box having a bottom inclined transversely and longitudinally towards one end and a drain opening arranged within the lower end of said box.

In testimony whereof I have hereunto affixed my signature.

ROY A. MANNING.
